ELECTROMECHANICAL AMPLIFIER

Howard H. Smith, Chicago, Ill., assignor to Peru
Radio Laboratories, Inc., Peru, Ind., a corpora-
tion of Illinois

Application February 9, 1938, Serial No. 189,613

10 Claims. (Cl. 179—171)

This invention relates broadly to amplifiers, and more particularly to the electromechanical variety in which currents to be amplified are translated into mechanical movement for the purpose of actuating some form of mechanical current varying device, such as a microphone, connected in circuit with an auxiliary source of power whereby the mechanical movement may be translated back through the current varying device into current variations of increased magnitude.

Stated more particularly, an important object of the invention is an improved electromechanical amplifier of the type which includes an electromagnetic element mechanically connected to a microphone such that primary or input signals of sufficient strength to operate the electromagnetic device will effect operation of the microphone which is arranged in circuit with a local source of power and is capable of effecting current variations of considerable magnitude compared with the slight mechanical movements resulting from the input signal variations.

Another object of the invention is the provision in electromechanical amplifiers, of improvements in certain structural features of the electromagnetic as well as the microphone elements.

Another object is the provision in electromechanical amplifiers of the type characterized, of certain improvements in the construction of a moving primary coil element and means for maintaining a magnetic field in which said primary coil may react responsive to current variations therein, the coil being mechanically connected with a microphone in a secondary circuit.

Another object is the provision of a microphone structure of the compound variety having a diaphragm of light-weight alloy to reduce its inertia constants, with microphone elements arranged on opposite sides of the diaphragm and within the peripheral margins of the latter such that the diaphragm may be rigidly attached to the axial end portions of the moving primary coil.

Another object is the provision of improvements in means for maintaining a magnetic field, said means including a magnetic structure of high efficiency and arranged to provide a mounting for the amplifier elements.

Another object is the provision of an improved moving coil structure including a spider mounting for the moving coil which in turn is supported on the aforesaid mounting provided by the magnetic means and which, in addition to its simplicity, is highly efficient for its intended purpose.

Another object is the provision in an amplifier of the type described of a moving coil system including a tubular coil mounting attached at one end to a compound microphone diaphragm, and spaced bracket members for mounting the compound microphone with one of the bracket members extending through cut-away portions in the tubular member so that the moving coil and the diaphragm may be mounted concentrically to permit shifting movement of the tubular member or coil in opposite directions to operate both elements of the compound microphone.

Other objects and novel aspects of the invention reside in the particular combination and construction of parts for achieving the several objects heretofore recited and in providing an amplifier of simple construction capable of full wave amplification and of increased frequency range.

The invention will be described with reference to the accompanying drawing, in which:

Fig. 1 is a top plan view of the amplifier;

Fig. 2 is a side elevation viewed in the direction of lines 2—2 of Fig. 1;

Fig. 3 is an enlarged fragmentary vertical me- 25 dian section along lines 3—3 of Fig. 1; while

Fig. 4 is a circuit diagram illustrative of one application of the amplifier.

The particular improvements in the art of electromechanical speakers contributed by the present invention provide an amplifier capable of greater fidelity and wider frequency response than amplifiers of this class heretofore developed, the improved performance of the present amplifier being due to certain features of construction 30 in providing a more efficient magnetic circuit 35 while at the same time simplifying the magnetic structure, a light-weight moving coil system and means for mounting the same for a wider frequency response of increased constancy, and a 40 microphone arrangement including a diaphragm constructed from a very light-weight alloy and attached to the axial end of the voice coil in the region of the periphery of the diaphragm.

A preferred embodiment of the invention, as 45 seen in Fig. 3, includes a support comprised of a permanent magnet 10 of cylindrical form and magnetized in the direction of its major axis. This permanent magnet if desired, however, may be in the form of a rectangular block of the shape 50 of the top pole plate seen in Fig. 1, but provided with an annular bore, and magnetized in the same manner. In the present instance, the member 10 may be considered a cylinder.

Mounted at one axial end of the cylindrical 55

magnetic member is a backing plate 11 provided with an axially extending magnetic pole member 12 preferably in the shape of a cylinder and attached by any convenient means, such, for example, as the reduced flared end portion 13 in the plate 11.

The magnetic circuit is substantially completed by means of a pole plate 14 fitted onto the opposite axial end or side of the cylindrical magnet, 10 both the backing plate 11 and the pole plate 14 being clamped against the intermediate magnetic member 19 by means of bolts and nuts 15 and 16. It is important to observe that the pole plate has a cut-away or open portion 17 which 15 fits over the free end portion 18 of the pole piece 12 and in spaced relation to the latter so as to provide an air gap in which the magnetic flux in the magnetic circuit for the permanent magnet 18 may be concentrated for purposes 20 hereinafter appearing.

The backing plate 11 and pole plate 14 in assembled relation with the magnetic member 10 comprise a form of magnetic structure constituting a support or mounting for the remaining elements of the amplifier. Attention is called to the rectangular form of the top or pole plate 14 as it appears in Fig. 1, for example. Where this form of construction is preferred, the magnetic member 10 may be in the form of a cylinder or 30 may be simply a ring-like member with rectangularly arranged exterior wall surfaces corresponding to the shape of the plates 11 and 14.

It may be remarked at this juncture that the means for providing a magnetic field in the region of the air gap 17 may also take the form of a winding about the pole piece 12, for example, and connected to a local battery for the purpose of setting up a field of variable intensity depending upon a regulation of the current flow and the nature of the winding. In such a case, of course, the permanent magnet 10 might be replaced by an unmagnetized element.

The moving coil system for the electromagnetic part of the amplifier includes a tubular member 19 in the form of a cardboard or fiber tube of the lightest possible weight consistent with the requisite rigidity to withstand the range of mechanical stresses placed upon it. This tubular member is of a diameter slightly larger than that of the pole piece 18 and such that the tube may fit freely in the air gap between the pole piece and the surrounding margins of the opening of the pole plate 14. Between its axial ends the tube 19 is rigidly attached as at 20 to a spider 21, the latter being formed of suitably processed paper or other fibrous material impressed with a plurality of undulations 22 by means of which the tube 19 is permitted freedom of movement in the direction of its axis but is allowed only a negligible freedom in other directions. The connection 20 between the spider and the tube 19 is preferably formed by application of a light-weight cement resistant to atmospheric changes and of a type which will not become crystallized or brittle or become loosened by the constant vibration of the coil system. Such cements are well-known in the art and therefore not specified herein. The important thing is that the connection or attachment of the tube 19 to the spider or other suspending means 21 be such as will assure maximum response and reaction movement of the coil in the line of its axis.

The outer end 23 of the spider is similarly cemented to the offset portion 24 of a mounting ring 25 arranged concentrically with the pole 75

piece 18 on the outside of the top or pole plate 14 (see Fig. 1). The ring 25 is clamped in place by the bracket or bridge construction for the microphone hereinafter to be described.

Near its lower end 19' the tube 19 for the voice coil is provided with a primary or reaction winding 26 extending inwardly to the region of the end of the pole piece 18 so as to lie substantially within the air gap 17, this winding 26 being adapted for connection by light-weight flexible conductors 27 and 28 (Fig. 1) in the primary or input circuit so that current variations in the latter will react in the magnetic field across the air gap 17 to cause the entire moving or voice coil structure including the tube 19 to shift or vibrate in an axial direction, correspondingly. 15

Referring still to Fig. 3, it will be observed that at its upper end '9" the voice coil tube 19 is attached as at 29 to the peripheral portions of a diaphragm 30. This diaphragm is desirably of the very lightest weight consistent with the requisite mechanical durability for a particular class of service, and is preferably made of a light-weight alloy such as Duralumin.

The diaphragm 36 is of annular shape corresponding closely to the diameter of the tube 19 and is attached to the latter preferably by means of a cement such as heretofore characterized, but may also be crimped onto the latter, if desired. 25

A microphone structure cooperable with the moving coil system includes a main bracket or bridge member 31 having offset end portions 32 provided with bolt holes through which extend bolts 33 rigidly securing the bridge to the main support or mounting structure, particularly the top or pole plate 14, the bridge extending across the middle of the pole plate with its under side spaced appreciably above the upper or free end 18 of the pole piece 12. A cup-shaped stationary electrode 34 is secured to the under side of the bridge by means of a central stud 35 extending through an insulating sleeve 36 for engagement with a connection lug 37 and a nut 38, the under side of the electrode 34 being kept out of contact with the bridge by an insulating strip 39 extending thereacross.

A spaced mounting portion or bracket in the form of a second bridge member 40 is secured to the under side of the main bridge 31 by means of bolts 41 extending through offset end portions 42 in the bridge and through insulating sleeves 43 seated in holes in the bridge 31 for engagement with a connection lug 44 and nuts 45. It should be observed that the particular upper end 55 of the tube 19 adjacent the diaphragm 30 is provided with cut-out portions 46 permitting the bridge member 40 to pass therethrough.

The smaller bracket 40 constitutes a spaced mounting portion for the main bridge to which is secured a second cup-shaped microphone electrode 47 riveted as at 48 to the smaller bridge or bracket portion opposite the first-mentioned electrode 24 and on an opposite side of the diaphragm 30 to the same. Fitting closely between the cup portion and corresponding side of the diaphragm are two felt rings 49, and arranged between the diaphragm in each of the cup portions within these felt rings is a current varying element or substance, for example, carbon granules 50.

It will be apparent that axial movement of the tube 19 will transmit corresponding movement to the diaphragm 30, and the microphone element on one side of the diaphragm will be ac- 25

tuated in one manner while the microphone element on the opposite side will simultaneously be actuated in an opposite manner. Stated in other terms, when the diaphragm 30 is driven in one direction by the tube, the carbon granules on one side thereof will be compressed while those on the opposite side will be decompressed or loosened. Thus, the arrangement of microphone elements provides a compound microphone which may be connected in accordance with the circuit diagram of Fig. 4, for example, to provide full wave amplification.

Referring to Fig. 4, a simple circuit arrangement utilizing this amplifier includes an input transformer 51 which may be connected in a primary or signal circuit with its output or secondary 52 connected with the moving coil winding 26. The movable actuating element or diaphragm 30 is connected by a conductor 53 to one side of a battery 54, the opposite side of this battery being connected by a conductor 55 to the center tap of a primary 56 of an output transformer, the other terminals of the primary winding being connected respectively by conductors 57 and 58 (through lugs 37 and 44 on the unit) with the stationary or cup-shaped electrodes 34 and 47, respectively. The secondary 59 of the output transformer is connected to any utilization means such as a loud speaker or the like.

It will be apparent that in accomplishing the objects of the invention and particularly in providing a moving coil system and means for mounting the same so as to achieve a maximum efficiency in translating electrical impulses into mechanical impulses, that the specifically described means may be varied within the spirit of the invention as it is defined by the appended claims. Moreover, in specifically setting forth herein a particular means for connecting the moving coil system with a microphone for full wave amplification so as to translate the mechanical impulses back into electrical impulses of increased amplitude without sacrificing fidelity or frequency response, various modifications and rearrangements are possible without departing from the invention or the call of the claims. Likewise, while I have endeavored to set forth what I consider to be the most suitable and efficient magnetic element construction and bridge means for attaching the moving coil and microphone system together so as to provide a compact and rugged unit, other arrangements may achieve the immediate objects of the invention as set forth in the claims. It is, therefore, my intention to include within the call of these claims all equivalent arrangements with respect both to form and location of the improved amplifying means disclosed.

What I claim as new and desire to protect by Letters Patent of the United States, is:

1. An electromechanical amplifier including means providing a mounting, a planar-like spider supported on said mounting, a signal coil including a tube portion secured between its ends to said spider with its axis transverse to the plane of the spider, means forming part of said mounting and providing a magnetic field for said signal coil, a microphone arranged on said mounting opposite an axial end of the signal coil and including an annular actuating diaphragm of minimized weight rigidly secured adjacent its peripheral portions to peripheral end portions of said signal coil tube, said signal coil being connected in a primary circuit and said microphone being connected in a secondary cir-

cuit such that energy variations in the signal coil will effect axial movement of the latter to move said diaphragm and actuate the microphone to effect corresponding variations in said secondary circuit.

2. An electromechanical amplifier including a mounting constructed of paramagnetic material and including means cooperable therewith providing a magnetic field, an input coil having a tubular mounting connected between its axial ends to a yieldable spider member constructed to permit movement of said coil including said tube in the direction of its axis, said spider having support on said mounting, a microphone including a pair of spaced electrodes aligned in spaced relation with the axis of said tube, a light-weight diaphragm disposed between said electrodes and having rigid attachment to the axial end portions around the periphery of an axial end of said tube, together with compressible conductive material confined between said electrodes and said diaphragm for activation by the diaphragm when said tube is moved responsive to current variations in said coil, said coil being arranged for connection in a primary circuit, 25 said diaphragm and electrodes of the microphone being arranged for connection in a secondary circuit.

3. An electromechanical amplifier including a substantially cylindrical permanent magnet having a paramagnetic backing plate mounted on one axial end thereof, a pole piece arranged coaxially within said cylindrical magnet and attached at one end to said backing plate, the opposite end thereof being free, a paramagnetic pole plate on the opposite axial end of said cylindrical magnet and having open portions spacedly surrounding said free end of the pole piece whereby to provide a concentrated magnetic field in the region of said free end, said cylindrical magnet, 35 backing plate, and pole plate constituting a mounting, a light-weight tube having an end portion fitted freely over said free end of the pole piece for axial movement between the latter and said pole plate, said tube being rigidly attached at a point between its ends to a spider mounted by means attached to said mounting such that said tube may shift in the direction of its axis relative to said pole piece, a compound microphone including an actuating diaphragm arranged between a pair of electrodes and having rigid attachment around its periphery to an axial end of said tube such that shifting of the tube will actuate said microphone, a primary coil wound on said tube in the region of said free end of the pole piece for connection to an input circuit, said microphone being connected with a source of power in an output circuit.

4. An electromechanical amplifier including a magnetic structure of substantially cylindrical shape and having an axially extending pole piece with a free axial end, a primary coil mounted for axial movement toward and away from said free end of the pole piece, said primary coil including a tubular mounting having an axial end portion extending beyond the axial extremity of the pole piece, a conductive diaphragm member of annular shape secured around its periphery to peripheral portions of said particular end of the tubular mounting, and a compound microphone having one electrode mounted on a bridge member secured to said magnetic structure and bridged over said particular axial end of the tubular member, said electrode including current varying means mounted between the same and 75

- the corresponding side of said diaphragm, and a second electrode secured to a second bridge member on the opposite side of said diaphragm, said second bridge member being attached to the under side of said first-mentioned bridge member, said second electrode also having current varying means arranged between the same and the corresponding side of said diaphragm, means for connecting said diaphragm and said several current varying means in a secondary circuit including a source of power, said primary coil being connected in a primary circuit, current variations in which effect axial movement of said tubular member to actuate said several current varying means by movement of said diaphragm.
5. In an electromechanical amplifier, means providing a support, a bridge member mounted on said support and a smaller bridge member mounted on the under side of said first-mentioned bridge member to provide spaced parallel bridge portions, microphone elements mounted in opposite relation on each of said spaced parallel portions and having therebetween a common actuating diaphragm of annular shape with peripheral portions extending beyond said microphone elements, a light-weight tube secured at one axial end to peripheral portions of said diaphragm such that axial movements of the tube will actuate both microphone elements, said tube having cut-away portions near said axial end through which portions of said second bridge member pass, yieldable means secured to said tube and mounted on said support and so constructed as to permit substantial freedom of movement of said tube in an axial direction and negligible movement in other directions, a primary winding on said tube near the end thereof remote from said diaphragm for connection in a primary signal circuit, said diaphragm and microphone elements being connected in a secondary circuit including a source of power, together with magnetic means mounted on said support and projecting axially within said tube in the region of said winding for concentrating a magnetic field in the region of said winding.
6. In an electromechanical amplifier, a light-weight annular diaphragm having independent microphone elements arranged on opposite sides thereof for simultaneous actuation thereby, said diaphragm and microphone elements being arranged for connection in a secondary circuit including a source of power, a magnetic structure providing a support, a bracket structure mounted on said support and including spaced portions to each of which one of said microphone elements is attached with said diaphragm therebetween, a tubular member having cut-away portions near a particular axial end thereof and fitted over a part of the spaced means of said bracket structure with said particular axial end thereof rigidly attached to said diaphragm such that said tubular member may be moved in an axial direction to actuate said diaphragm and said micro-

phone elements, spider means attached to said tubular element between its axial ends and secured to said support so as to permit freedom of movement of the tubular member in an axial direction for the purpose aforesaid, a primary winding on said tubular member adjacent an end thereof opposite said diaphragm, and magnetic pole means forming part of said support and extended within said tubular member for the purpose of concentrating magnetic lines of force in the region of said winding, said amplifier including means arranged as a part thereof for producing a magnetomotive force inducing lines of force through said winding into said magnetic pole means.

7. In an electromagnetic amplifier, a primary coil structure comprising a coil and supporting tube therefor, said tube being attached at one of its axial peripheral extremities to a diaphragm arranged as a common operating element between opposite differential electrodes of a differential type microphone, said coil being movable principally in axial displacement to actuate said diaphragm between said electrodes.

8. In a device of the class described, a microphone and primary coil mechanism which includes a microphone having a substantially planar operating element, a primary coil structure of tubular form attached at one axial periphery to said planar operating element with the axis of the coil concentrically normal to said planar element, and means extended in a plane substantially parallel to that of said planar element and supportably engaging said coil structure between its ends for axial displacement.

9. In an amplifier of the class described, a microphone and signal coil mechanism including a differential microphone having a pair of differential electrodes with a common substantially planar actuating element arranged therebetween for coaction with the same and current varying means by movement of the planar member in opposite directions normal to its plane, and a signal coil structure of tubular shape attached in the region of the periphery of one of its axial ends to said planar actuating element, and means supportably engaged with said coil structure and arranged to permit axial displacement thereof.

10. In a moving coil device, a coil structure comprising a tubular coil carrier and a coil thereon, said carrier having a diaphragm mounted rigidly in the plane of one of its axial ends, said diaphragm being adapted for cooperation with an instrumentality to be operated by movement of said coil structure, and means extending substantially in a plane transverse to the axis of said coil structure and supportably engaged with the latter in a region between the ends thereof and constructed and arranged to permit axial displacement of the coil structure.

HOWARD H. SMITH.
